SPARK PLUG

William K. Andersen, Brooklyn, N. Y.

Application February 10, 1936; Serial No. 63,054

7 Claims. (Cl. 123—169)

This invention relates to an improvement in spark plugs for internal combustion engines and more particularly to a means incorporated in the spark plug for providing a supplemental spark intensifier between the center electrode and terminal screw when the plug is in a cold condition, and which means automatically closes the gap and eliminates the spark when the means is heated by the explosion of the gases within the engine cylinder.

One object of the invention is to provide a spark plug having enclosed therein a thermostatic element connected with the center electrode and normally spaced from the terminal screw connection to form a relatively small spark gap which is closed when the element is heated, thereby intensifying the initial effect of the electrical current and increasing the action of the spark delivered at the fixed or permanent spark gap in the usual manner.

Another object is to provide certain improvements in the form, construction, and arrangement of the parts, whereby the above named and other objects may effectively be attained.

A practical embodiment of my invention is represented in the accompanying drawing, in which

Fig. 1 represents a vertical central section of a spark plug having my improvements incorporated therein;

Fig. 2 represents a similar view of the upper portion of the spark plug with the parts in another position; and

Fig. 3 represents a horizontal section taken in the plane of the line III—III of Fig. 1, looking in the direction of the arrows.

The body of the spark plug is of conventional form and denoted by 1, the interior bores by 2, 3, the insulator by 4, the clamp nut by 5, which is screw threaded in the threaded bore 6 of the body and secures the insulator in position in the bores 2, 3 of the body. The body 1 is exteriorly screw threaded at 7 for affixing it to the cylinder of the internal combustion engine (not shown) in the well known manner. A fixed electrode 8 extends from the lower end of the body and is disposed to coact with the center electrode 9 secured in the insulator 4, between which electrodes 8 and 9 the permanent and comparatively wide spark gap is formed. This center electrode 9 is fixed in the insulator by means of a bushing 10 which is secured at its upper end by being shrunk therein or secured by any well known or approved means. The bushing 10 is screw threaded at 11 to engage the screw threaded bore 12 in the insulator. These screw threaded portions 11 and

12, together with the electrode 9 are permanently fixed in the insulator by means of cement or other suitable means. The upper end of the insulator 4 is formed with a screw threaded bore 13 arranged to receive the screw threaded portion 14 of the terminal connector 15. This connector 15 is provided with a screw threaded shank 16 and nut 17 for the reception of the distributor wire (not shown). The connector also has a concentric chamber 18 in open communication with the bore 13 of the insulator 4 and radial openings 19 leading from the chamber 18 to the outside, so that air may be freely admitted to and from the chamber to serve as a peep sight as well as cool the plug.

A thermostatic element comprising, in the present instance, a pair of fingers 20, 21 disposed in intimate contact with each other and having their lower ends permanently fixed in a recess 22 in the upper end of the bushing 10 and in longitudinal alignment with the electrode 9. The fingers 20, 21 extend upwardly from the bushing 10 through the bore 13 into the chamber 18 of the connector 15, and the upper ends thereof are bent outwardly away from each other, as shown at 23, 24, respectively. The bent upper ends 23, 24 of the fingers are disposed above the radial openings 19 in position to be normally spaced a relatively small distance away from the interior wall of the chamber 18, thereby forming narrow spark intensifying gaps 25, 26. Each of the fingers 20, 21 is composed of two metallic plates having different coefficients of expansion when subjected to heat, such as brass and nickel, steel or the like. The plates in each of the fingers are permanently and fixedly united throughout their entire contacting surfaces and are so arranged that the adjacent surfaces of the fingers, when assembled in the plug, will be of the similar material, such as brass to brass, etc.

Thus, it will be seen that when the spark plug is cold, the parts will assume the position shown in Figs. 1 and 3, in which position the fingers 20, 21 of the thermostatic element will be in intimate contact with each other throughout their length, while the upper bent ends 23, 24 will be spaced from the walls of the chamber 18. When an electrical impulse is passed through the distributor wire (not shown) to the connector 15 through the shank 16 and nut 17, the current will jump across the gaps 25, 26 between ends 23, 24 of the fingers 20, 21 and the wall of the chamber 18, after which it will pass downwardly through the fingers and bushing 10 to the electrode 9 whence it will again cross to the fixed electrode 8 and

ignite the gases in the cylinder of the engine (not shown). By igniting the gases in the cylinder the spark plug as a whole will become heated, which heat being carried through the electrode 9, bushing 10 and fingers 20, 21 will cause the brass surfaces of the fingers to expand and flex the fingers above the bushing 10 so that they will move in opposite directions away from each other at the upper ends. This outward movement of the fingers 20, 21 will bring the bent ends 23, 24 respectively, into contact with the wall of the chamber 18 and thereby close the gaps so that the electrical impulse will be passed directly through the connector 15, fingers 20, 21, bushing 10, and electrode 9 where the firing spark will be formed with the fixed electrode 8 in the usual manner. When the electrical impulses which form the spark cease, and the spark plug, together with its associated parts have become cool, the fingers 20 will re-flex and return to their normal position, so that the bent ends 23, 24 of the fingers will be spaced from the wall of the chamber 18 and set ready to receive the initial electrical impulse for starting the engine. From the foregoing it will be seen that I have devised a spark plug having an automatically operated thermostatic element forming a part of and incorporated within the spark plug structure, which element tends to produce an intense initial spark or sparks between the fingers and the terminal screw, and from which the electrical energy is carried to the center electrode to bridge the fixed gap where a firing spark ignites the gases in the cylinder more readily so that the engine is started much easier when cold.

It will be understood that various changes may be resorted to in the form, construction and arrangement of the several parts without departing from the spirit and scope of my invention, and hence I do not intend to be limited to the details herein shown and described except as they may be included in the claims.

What I claim is:

1. A spark plug having in combination with its permanent spark gap a supplemental spark intensifying gap, and a thermostatically operated element arranged to close said supplemental gap when the plug is heated.

2. A spark plug having in combination with its fixed and center electrodes forming its permanent spark gap, a terminal connector, a thermostatically operated element connected with the center electrode and arranged to form a supplemental spark intensifying gap between it and said terminal connector when the plug is cold and actuated to close said supplemental gap when heated.

3. A spark plug comprising a body having a fixed electrode, an insulator carried by said body and provided with a center electrode, a terminal connector secured to said insulator and spaced from said center electrode, and a thermostatically operated element connected to the center electrode and extending upwardly therefrom in position to contact with said terminal connector when heated and break contact therewith to form a supplemental spark intensifying gap therebetween when cold.

4. A spark plug comprising a body having a fixed electrode, an insulator carried by said body and having a hollow outer end, a center electrode

secured in the inner end of said insulator and arranged to coact with said fixed electrode to form a permanent spark gap, a terminal connector secured to the outer hollow end of said insulator and spaced from said center electrode, and a thermostatically operated element connected to the center electrode and extending upwardly therefrom into the hollow end of the insulator in position to be brought into contact with said terminal connector when heated and break contact therewith to form a supplemental spark intensifying gap therebetween when cold.

5. A spark plug comprising a body having a fixed electrode, an insulator carried by said body and having a hollow outer end, a center electrode secured in the inner end of said insulator and arranged to coact with said fixed electrode to form a permanent spark gap, a terminal connector secured to the outer hollow end of said insulator and spaced from said center electrode, said terminal connector having a chamber therein, and a thermostatically operated element connected to the center electrode and extending upwardly therefrom into said chamber in the terminal connector in position to be brought into contact with the walls of the chamber when heated and break contact therewith to form a supplemental spark intensifying gap therebetween when cold.

6. A spark plug comprising a body having a fixed electrode, an insulator carried by said body and having a hollow outer end, a center electrode secured in the inner end of said insulator and arranged to coact with said fixed electrode to form a permanent spark gap, a terminal connector secured to the outer hollow end of said insulator and spaced from said center electrode, said terminal connector having a chamber therein, and a thermostatically operated element comprising at least two members connected at their lower ends to the center electrode and extending upwardly therefrom into said chamber in the terminal connector, the free ends of said element being disposed to be moved in opposite directions toward and away from each other so as to be brought into contact with the walls of the chamber when heated and break contact therewith to form a supplemental spark intensifying gap therebetween when cold.

7. A spark plug comprising a body having a fixed electrode, an insulator carried by said body and having a hollow outer end, a center electrode secured in the inner end of said insulator and arranged to coact with said fixed electrode to form a permanent spark gap, a terminal connector secured to the outer hollow end of said insulator and spaced from said center electrode, said terminal connector having a chamber therein, and a thermostatically operated element comprising at least two members connected at their lower ends to the center electrode and extending upwardly therefrom into said chamber in the terminal connector, the free ends of said element being bent outwardly and disposed to be moved in opposite directions toward and away from each other so that the bent ends will be brought into contact with the walls of the chamber when heated and break contact therewith to form a supplemental spark intensifying gap therebetween when cold.
